FOLDING HIGH CHAIR

Application filed January 25, 1928. Serial No. 249,285.

Our invention relates to high chairs and has for its object to provide a high chair which may be readily and quickly collapsed into a small compact space so as to permit of being easily carried about or to be packed away in crowded quarters when not desired for use.

Another object of the invention resides in providing a pair of frame sections each comprising two spaced uprights connected together at their upper and lower ends, which uprights are pivoted intermediate their ends so as to permit the same to be swung into a common plane or swung outwardly and extended in crossed relation.

Another object of the invention resides in forming one of said frame sections longer than the other and in hingedly connecting to the upper portion of said shorter frame section a seat adapted to extend across said longer frame section and in further attaching a support to said longer frame section on which said seat is adapted to rest when the chair is arranged in operative position, said seat being adapted to swing between the two frame sections when it is disengaged from said support.

An object of the invention resides in pivoting to said longer frame section a pair of arms embracing the same and extending toward said shorter frame section and being supported at their outer ends thereon, and further attaching to said arms a tray adapted to swing therewith over the upper end of said longer frame section.

A feature of the invention resides in pivotally connecting to said arms a pair of downwardly extending slats and in attaching loops to said seat for the reception of said slats for the purpose of closing the space between said frame sections when the same are in extended position, said slats being adapted to fold within said tray when the chair is in collapsed position.

An object of the invention resides in pivot-

ing between the uprights of the lower frame section a back rest adapted to swing outwardly into a position to engage the back of a user or to be folded back between the uprights of said longer frame section into the plane thereof to give support to the back of the occupant in either an upright or reclining posture.

A feature of the invention resides in providing a foot rest and in pivoting the same to said frame sections at the hinge thereof, said foot rest being arranged between the uprights of the longer frame section and being adapted to swing into the plane thereof when in disuse.

Another object of the invention resides in attaching a strap to the tray adapted to be threaded through an eye formed on said tray and in providing a fastener on said strap adapted to cooperate with a complementary fastening member secured to the seat for holding the tray immovable relative to the seat when in operative position and to prevent the child from sliding off the seat.

A feature of the invention resides in offsetting the hinge connections of said tray and seat so as to cause the same to fold to either side of the frame sections when in collapsed position and in further providing a second complementary fastening member attached to said seat and adapted to be engaged by said strap fastener when said strap has been disengaged from said eye for holding said parts in collapsed position.

With the foregoing and other objects in view, which will appear in the following description, the invention resides in the novel combination and arrangement of parts and in the details of construction hereinafter described and claimed.

In the drawings:

Fig. 1 is a perspective view of a high chair embodying one form of our invention.

Fig. 2 is a side elevational view of the structure shown in Fig. 1 with some of the

parts partially folded back to illustrate the method of collapsing the same.

Fig. 3 is a side elevational view of the structure when in collapsed position.

Fig. 4 is an inverted view of the structure shown in Fig. 3.

In the care of infants considerable time is saved and convenience afforded the parents or nurse during meal time when the infant is securely positioned within a high chair. In visiting, it frequently occurs that a high chair is not available for this purpose and it hence becomes exceedingly annoying to take infants along and to feed the same under such circumstances. Our invention provides a simple and convenient high chair which may be quickly and readily collapsed to occupy a small space so that the same may be carried in an automobile and may be available wherever desired for the required purpose. In addition, the chair when not desired for use may be folded up and placed out of the way where the same can at any time be erected when desired for instant use.

* In the form of our invention shown in Fig. 1, we employ two frame sections 10 and 11 of which the frame section 10 comprises two uprights 12 and 13 connected together at their lower ends by means of a transverse cleat 14. The frame section 11 comprises two uprights 15 and 16 which are similarly connected together at their lower ends by means of a cleat 17 and which are connected together at their upper ends by means of a cleat 18.

It will be noted that the cleat 17 is attached to the uprights 15 and 16 on one side thereof, while the cleat 18 is attached to the said uprights on the other side thereof for a purpose which will presently become apparent.

The two frame sections 10 and 11 are hingedly connected together intermediate their ends by means of two pintles 19 which extend through the respective uprights 12 and 13 and the uprights 15 and 16. By means of these two pintles the two frame sections may be folded into a common plane or may be extended in crossed relation, as best shown in Fig. 1. At the lower end of said frame sections are attached two knee braces 20 and 21 which limit the extended position of said frame sections and which permit of folding the same into a common plane. The lower portions 22, 23, 24 and 25 of the uprights 12, 13, 15 and 16 form legs for the chair and are preferably cut at the proper bevel so as to provide a suitable footing for the chair when the same is placed upon the floor. The uprights of the respective frame sections 10 and 11 are preferably flared outwardly along the lower portions thereof so as to make the chair more stable when in erected position.

Between the uprights 12 and 13 of the frame section 10 is pivotally connected a seat 26 by means of hinges 27 which are arranged with the axes thereof in offset relation to the

plane of the seat so that when the seat is swung upon its hinges, the same may occupy the position shown in Fig. 1 or may be folded back into a plane parallel with the common plane of frame sections 10 and 11 when in collapsed position. The seat 26 extends rearwardly toward the frame section 11 and is carried at its rearward end upon a support 127 similar to the cleats 17 and 18 attached to the uprights 15 and 16 of said frame section. This seat rests freely upon said support and is held in operative position solely through the weight of the user. The seat serves to brace the upper ends of the uprights 12 and 13 to which it is pivoted.

As will be noted in the drawings the frame section 11 is somewhat longer than the frame section 10 and extends upwardly beyond the same. Intermediate the seat support 27 and the cleat 18 is pivotally connected between the uprights 15 and 16 of said frame section, a back rest 28 which is adapted to swing into extended position as shown in Fig. 1 or which may be folded back into the plane of the frame section 11 when desired. This back rest comprises two stiles 29 and 30 connected together by means of rails 31 and 32 having slats 33 positioned between the same for providing a suitable back support. Said back rest is pivoted to the frame section 11 by means of pintles 34 which pass through the uprights 15 and 16 and through the lower ends of the stiles 29 and 30 which project somewhat below the lower rail 32 for this purpose. At the upper portion of said stiles are attached two knee braces 35 which limit the outward movement of said back rest and permit the same to be folded into the plane of the frame section 11. With this construction it can readily be comprehended that the uprights of the various frame sections may be made substantially straight and that the distance between the forward portion of the seat 26 and the rearward part of the frame section 11 occasioned by the flaring of the two frame sections can be greatly reduced through the use of the said back rest so that the infant is properly seated upon the chair when the same is in operative position. At the same time by folding the back rest into the plane of the frame section 11 the infant may be supported in a reclining position. The cleat 18 previously referred to is so arranged relative to the back rest 28 that the same forms a suitable end support for said back rest when the same is folded back into the plane of the frame section 11.

In conjunction with the seat 26 we employ a tray 36 which has attached to it two arms 37 and 38. These arms are arranged to straddle the two uprights 15 and 16 of frame section 11 and are hingedly connected to it by means of two pintles 37. The ends of said arms are preferably offset as indicated at 38, and the said arms are of such length as to

5 permit the tray to be swung over the upper end of the uprights 15 and 16 into a position upon the back of the frame section 11 lying in a plane substantially parallel with the common plane of the two frame sections when in collapsed position, as best shown in Fig. 3. For the purpose of closing the space between the two frame sections and the arms 37 and 38 and seat 26, we employ two slats 10 39 and 40 which are pivoted at 41 and 42 to the arms 37 and 38 and which are adapted to extend downwardly and be received in loops 43 attached to the sides of said seat 26. These slats are so disposed that the same may 15 be swung into the tray 36 as illustrated in Fig. 2 so as to be enclosed within the same when the chair is fully collapsed. These slats prevent the infant from slipping sideways out of the chair and also serve to hold 20 the tray 36 more rigidly in operative position.

For supporting the feet of the infant we employ a foot rest 44 which is attached to two arms 45 and 46. These arms are hinged- 25 ly connected upon the pintles 18 and 19 used for pivoting the two frame sections 10 and 11. The foot rest 44 may be swung into extended position as shown in Fig. 1 or the same may be swung into the plane of the frame section 30 11. For holding the said foot rest in extended position arms 45 and 46 are provided with ears 47 which are adapted to engage stops 48 secured to the uprights 15 and 16. This construction limits the downward move- 35 ment of the foot rest but permits the same to be swung upwardly and into the plane of the frame section 11. It will be noted that the arms 45 and 46 are of such a length as to permit the same to swing past the seat 16 when 40 the said seat is elevated, as will be presently described.

For the purpose of holding the tray 36 in fixed position relative to the seat 26 we employ a strap 49 which is attached to the under- 45 side of the tray 36 near the central portion of the same. This strap is adapted to be threaded through an eye 50 secured to the rearward part of the tray proper in a centrally disposed position between the arms 50 37 and 38 and to be drawn forwardly around the forward edge 50 of the seat 26. Upon the underside of the said seat is provided a post 51 which serves as a complementary fastening member adapted to engage a fastener 52 secured to the end of said strap 49. By means of this construction the tray is 55 firmly held in place, the said strap being arranged between the legs of the infant so as to prevent him from sliding outwardly from the chair between the seat and tray thereof as well as for holding the tray and seat in proper relative position.

In collapsing the chair the procedure is as follows: The back rest 28 is first moved from 60 its position as shown in 28^a in dotted lines

in Fig. 2 and into the plane of the frame section 11 as shown in full lines in said figure at 28^b, the knee braces 35 being broken to permit of the taking of such position. The strap 49 is next disengaged from the post 51 and the tray 36 moved from the position shown in dotted lines at 36^a to that shown in full lines at 36^b. As soon as the slats 39 and 40 become disengaged from the loops 43 the said slats may be folded back into the tray proper as illustrated in full lines at 40^b in said figure. Seat 26 is next raised upwardly from its position shown in dotted lines at 26^a and lowered to its position shown in full lines at 26^b. This permits of raising the foot rest 44 from position shown in dotted lines at 44^a to bring the same within the space between the uprights 15 and 16 of the frame section 11. It will be noted when so folded that the said foot rest rests upon the seat support 27 75 which prevents the same from swinging outwardly past the plane of said frame section. With the parts so arranged the knee braces 20 and 21 may next be broken and the two frame sections brought into a common plane. By 80 moving the frame sections together, the tray 36 and seat 26 follow so that the same lie flush with the said frame sections and in parallel planes thereto when the chair is fully collapsed. The arrangement of the parts when fully collapsed is shown in Fig. 3. For 85 the purpose of holding all of the parts together, the strap 49 is utilized. This strap is first disengaged from the eye 50 and is drawn through the two frame sections 10 and 11 and the fastener 52 is applied to a post 53 similar to the post 51 which is attached to the rearmost portion of the seat 26. By the proper attachment of the strap to the seat 90 the length of the same can be made such that the same strap serves to hold the parts in firm 95 position when collapsed or to hold the tray immovable relative to the seat when in extended position. When collapsed, the entire chair occupies a minimum amount of 100 space, as clearly shown in Fig. 3 and may be conveniently transported or stored in a confined space. In erecting the chair the procedure is exactly the reverse as when it is collapsed, the strap 49 being finally attached to the underside of the seat by application to 105 the post 51.

Our invention is highly meritorious in that a simple and effective device is provided, whereby the chair may be quickly and easily collapsed or erected, as required. The chair may be constructed at a nominal cost due to the fact that the same may be formed of straight pieces, thereby eliminating waste of wood or material used in the manufacture of 110 the same. The chair back may be adjusted to permit the user to sit erect or to be partly reclined, so that the chair may be used both at meal time and for permitting the infant to 115 rest. The chair is extremely sturdy and the 120

legs thereof have sufficient spread to cause the chair to stand firmly on the floor, thereby preventing overturning due to the antics of the user. By means of the slats connecting the tray arms and seat and the strap positioned between the legs of the infant, the infant is firmly confined within the chair and is unable to extricate himself therefrom without assistance so that danger of injury to the infant is practically eliminated while it is occupying the chair.

Changes in the specific form of our invention, as herein disclosed, may be made within the scope of what is claimed without departing from the spirit of our invention.

Having described our invention, what we claim as new and desire to protect by Letters Patent is:

1. A folding high chair comprising a pair of frame sections hingedly connected together intermediate their ends adapted to be folded substantially in a common plane or to be arranged in diverging relation, a seat pivoted to one of said frame sections, a member on the other frame section for supporting said seat, a tray pivoted at one end to the second frame section and adapted to be supported at its other end upon the first named frame section, and a back rest pivoted to said second named frame section in proximity to said seat support, said back rest being adapted to swing away from the upper portions of said frame section and toward said tray, and means for holding the parts in extended position.

2. A folding high chair comprising a pair of frame sections hingedly connected together intermediate their ends adapted to be folded substantially in a common plane or to be arranged in diverging relation, a seat pivoted to one of said frame sections, a member on the other frame section for supporting said seat, a tray pivoted at one end to the second frame section and adapted to be supported at its other end upon the first named frame section, and a back rest pivoted to said second named frame section in proximity to said seat support, said back rest being adapted to swing away from the upper portions of said frame section and toward said tray, a foot rest pivoted to one of said frame sections and adapted to extend outwardly therefrom into a position below said seat, said foot rest and back sections being adapted to fold in the common plane of said frame sections and said tray and seat being adapted to fold on opposite sides of said frame sections and to lie substantially parallel to the common plane thereof, and means for holding the parts in extended position.

3. A folding high chair comprising a pair of frame sections, each including a pair of spaced uprights, said uprights being hingedly connected intermediate their ends to permit said frame sections to be folded into a common plane or to be extended in crossed relation, one

of said frame sections being longer than the other, a seat pivoted to the shorter frame section and adapted to swing between the uprights thereof, a support secured to the longer frame section directly opposite said seat for holding the same in horizontal position, a pair of arms pivoted to the uprights of said longer frame section and adapted to rest upon the uprights of said shorter frame section, a tray secured to said arms, said arms straddling said longer frame section and adapted to swing over the upper end thereof, a back rest pivoted between the uprights of said longer frame section above the seat support thereof, and a foot rest pivoted between the uprights of said longer frame section below the seat support thereof, said foot rest and back rest being adapted to be extended outwardly in operative position or to be folded back into the plane of said longer frame section between the uprights thereof, said arms having the pivots thereof offset from the plane of said tray and said seat having the pivots thereof offset from the plane of said folded frame sections to cause said tray and seat to be folded to either side of said frame sections when collapsed so as to lie in planes substantially parallel with the common plane of said frame section, and means for holding the parts in extended position.

4. A folding high chair comprising a pair of frame sections, each including a pair of spaced uprights, said uprights being hingedly connected intermediate their ends to permit said frame sections to be folded into a common plane or to be extended in crossed relation, one of said frame sections being longer than the other, a seat pivoted to the shorter frame section and adapted to swing between the uprights thereof, a support secured to the longer frame section directly opposite said seat for holding the same in horizontal position, a pair of arms pivoted to the uprights of said longer frame section and adapted to rest upon the uprights of said shorter frame section, a tray secured to said arms, said arms straddling said longer frame section and adapted to swing over the upper end thereof, a pair of slats pivoted to said arms and adapted to extend downwardly therefrom and toward said seat, and loops formed on said seat for the reception of said slats for fencing the space between said frame sections above the seat, said slats being adapted to be folded upon said tray upon the collapsing of said chair, and means for holding the parts in extended position.

5. A folding high chair comprising a pair of frame sections pivoted to one another and adapted to be folded into a common plane or to be extended outwardly in crossed relation, a seat pivoted to one of said frame sections and extending across the same, a tray pivoted to one of said frame sections and supported upon the other, a strap secured to said tray,

5 a fastener attached to the end of said strap, a complemental fastening member secured to said seat for engagement with said strap fastener for holding the tray immovable relative to said seat when in extended position, and a second complemental fastening member secured to said seat for engagement with said strap fastener when said chair is in collapsed position, and means for holding the parts in extended position.

10 6. A folding high chair comprising a pair of frame sections pivoted to one another and adapted to be folded into a common plane or to be extended outwardly in crossed relation, a seat pivoted to one of said frame sections and extending across the same, a tray pivoted to one of said frame sections and supported upon the other, a strap secured to said tray, a fastener attached to the end of said strap, a complemental fastening member secured to said seat for engagement with said strap fastener for holding the tray immovable relative to said seat when in extended position, and a second complemental fastening member secured to said seat for engagement with said strap fastener when said chair is in collapsed position, an eye attached to said tray through which said strap is threaded for taking up the slack in said strap due to the positioning of said fastening members, said strap extending through said eye when attached to one of said fastening members and being removed therefrom when attached to the other fastening member, and means for holding the parts in extended position.

15 7. A folding high chair comprising a pair of frame sections, each including a pair of spaced uprights, said uprights being hingedly connected intermediate their ends to permit said frame section to be folded into a common plane or to be extended in crossed relation, one of said frame sections being longer than the other, a seat pivoted to the shorter frame section and adapted to swing between the uprights thereof, a support secured to the longer frame section directly opposite said seat for holding the same in horizontal position, a pair of arms pivoted to the uprights of said longer frame section and adapted to rest upon the uprights of said shorter frame section, a tray secured to said arms, said arms straddling said longer frame section and adapted to swing over the upper end thereof, a strap secured to said tray intermediate the forward and rearward edge thereof, an eye attached to said tray near the rearward edge, said strap being adapted to be threaded through said eye, a fastener attached to the end of said strap, a complemental fastening member secured to the underside of said seat in proximity to the pivotal connection thereof adapted to cooperate with said strap fastener for holding said tray immovable relative to said seat,

20 said tray and seat being adapted to be swung on either side of said frame sections when folded into their common plane, a second fastening member secured to said seat and adapted to cooperate with said strap fastener when said strap has been removed from said eye to hold said structure in collapsed position.

25 8. A folding high chair comprising a pair of frame sections hingedly connected together intermediate their ends adapted to be folded substantially in a common plane or to be arranged in diverging relation, one of said frame sections having the upper portions thereof extending rearwardly beyond the rearward portion of the other frame section, a tray pivoted to said rearwardly extending portion, a seat carried in part by said rearwardly extending portion and in part by the other frame section and a back rest pivoted to said rearwardly extending portions, said back rest being movable from a substantially vertical position to an inclined position, and means for holding the parts in adjusted position.

30 9. A folding high chair comprising a frame structure including a pair of frame members adapted to be folded into collapsed or extended position, a seat pivoted to one of said frame members, a tray pivoted to the other of said frame members, and a foot rest carried by said frame structure and adapted to be moved in the plane thereof when in collapsed position, said tray and seat being foldable in the collapsed position of said frame structure to overlie said foot rest on opposite sides thereof.

35 10. A folding high chair comprising a pair of frame sections hingedly connected together intermediate their ends and adapted to be folded substantially in a common plane or to be arranged in diverging relation, a seat pivoted to one of said frame sections and supported on the other, the other of said frame sections extending in marked inclined relation rearwardly with respect to said seat, and a back rest pivoted to said other frame in proximity to said seat support, said back rest being adapted to occupy an inclined position substantially within the plane of the frame section to which it is pivoted or to occupy a substantially vertical position rising immediately upwardly from the rear end of said seat, and means for holding the back rest in either of its extreme positions.

40 11. A folding high chair comprising a frame structure including a pair of frame members adapted to be folded into collapsed or extended position, a seat pivoted to one of said frame members, a tray pivoted to the other of said frame members, and a foot rest carried by said frame structure and adapted to be moved in the plane thereof when in collapsed position, said tray and seat being foldable in the collapsed position of said
